UNITED STATES PATENT OFFICE

LUCIEN LELONG, OF PARIS, FRANCE, ASSIGNOR TO LUCIEN LELONG, INC., OF CHICAGO, ILLINOIS, A CORPORATION OF ILLINOIS

DESIGN FOR A BOX OR SIMILAR ARTICLE

Application filed January 7, 1933. Serial No. 46,752. Term of patent 7 years.

To all whom it may concern:

Be it known that I, LUCIEN LELONG, a citizen of the Republic of France, and a resident of the city of Paris, France, have invented a new, original, and ornamental Design for a Box or Similar Article, of which the following is a specification, reference being had to the accompanying drawing, forming a part thereof.

On the drawing:

The figure illustrates an isometric perspective view of the box or similar article, embodying my invention.

I claim:

The ornamental design for a box or similar article, as shown.

LUCIEN LELONG.
